PROCESS FOR FINISHING ARTIFICIAL THREAD

Charles Chatin, Ixleux, France, assignor, by mesne assignments, to E. I. du Pont de Nemours & Company, Wilmington, Del., a corporation of Delaware

Application October 22, 1931, Serial No. 570,474
In France October 22, 1930

11 Claims. (Cl. 18—54)

This invention relates to the production of artificial thread. More particularly, this invention relates to the production of artificial thread from cellulosic solutions such as viscose. Still more particularly, the invention relates to an improvement in the handling and purifying of regenerated cellulose threads.

In the method of making artificial thread wherein a solution of cellulosic material is formed into threads and wound to a considerable thickness on a rigid bobbin and wherein the thread is subsequently purified and dried on the bobbin, the outer windings of thread, which are laid on the compressible under windings, shrink considerably in the purification and drying, whereas the windings close to the rigid core are prevented from shrinking. This causes the finished thread to have uneven denier, varying strength, and dyeing characteristics which are not uniform. In the past it has been found desirable to take the spun thread from the bobbin and reel it into loose skeins before purification, or to spin it onto non-rigid bobbins. These processes have not been entirely satisfactory, however, because, in the first process the yarn acquires broken filaments, knots, kinks and cut or broken threads through handling, and in the second process imperfect equalization and purification result.

It is an object of this invention to improve the manufacture of rayon. It is another object of the invention to improve the handling and purification of rayon threads of the regenerated cellulose type which have been spun on bobbins. Other objects of the invention will be in part apparent and in part set forth as the description proceeds.

These objects are accomplished by winding the thread upon a bobbin, rewinding with twisting, before purification, upon a second bobbin which is preferably provided with a liquid-permeable, collapsible, removable core, and removing the wound cake from the bobbin before treating.

In the accompanying drawing, Figure 1 is an elevation showing one method of accomplishing the rewinding; Figures 2 and 2a show a bobbin with one form of collapsible covering; Figures 3 and 4 show a bobbin with a collapsible covering used to protect a wound cake of rayon; Figure 5 illustrates one method of arranging the second bobbin for winding.

In Figure 1, numeral 1 indicates a bobbin; 2 is a cake of rayon wound upon the bobbin; 3 is the rayon thread; 4 is a guide for the rayon

thread; 6 and 61 are tension rods whose use is optional; 7 is a guide for traversing the thread onto the surface of the rewound bobbin; 8 is a rewind bobbin; 9 is a rewinding frame which holds the rewind bobbin; 91 is a rewind roller which drives the rewind frame. Numeral 5 designates a rotating mechanism for rotating bobbin 1.

In Figure 2, numeral 8 indicates a rewinding bobbin which is provided at one or both ends with no bead at all, with an inturned bead, or with a bead of size insufficient to prevent the easy withdrawal of the rewound cake; 10 is a collapsible covering consisting in this instance of a cloth having projecting ends which may be tucked inside the bobbin (as in Figure 3) during winding.

In Figure 3, numeral 21 is a rewound cake of rayon which may be provided, as shown, with square ends, or with bevelled ends.

In Figure 4, the cloth covering 10 has been withdrawn from the interior of the bobbin 8 and folded in protecting position over the outside of the cake. After the cake has been thus protected, it will be slipped off the bobbin, as indicated in dotted lines, and processed.

In Figure 5, numeral 9 indicates generally the rewinding frame which comprises two wheel-like ends connected by an axle, 92, which is preferably integral with one of the wheel-like ends but not with the other; 93 is a nut on the end of the axle, by means of which the rewind bobbin may be clamped between the wheels of the frame. In operation these wheels run upon and are driven by the surface of roller 91 as shown in Figure 1.

In the practice of this invention the thread may be either in the gel or in the dried state. A gel thread is one that has not been dried to equilibrium after being formed. A dried thread is one that has been brought to its equilibrium or standard moisture content.

A cloth covering for the rewind bobbin has been illustrated in the drawing, but coverings of other materials, such as suitable paper or cardboard coverings, may be used and, since they collapse in the purifying liquid, need not be removed before purification.

An advantage of my invention is an improvement in the quality of the yarn produced, as compared with customary methods. This improvement appears particularly in the increased uniformity of the thread and in its improved and more uniform dyeing properties. Yet another advantage lies in the improved method of han-

dling. Other advantages will be apparent to those skilled in the art.

As many apparently widely different embodiments of this invention may be made without departing from the spirit and scope thereof, it is to be understood that I do not limit myself to the specific embodiments thereof except as defined in the appended claims.

I claim:

- 10 1. In the manufacture of rayon, the process which comprises spinning rayon in cake form upon a bobbin rewinding with twisting into cake form upon a second bobbin, and removing the cake from the second bobbin before purifying the cake.
- 15 2. In the manufacture of rayon, the process which comprises spinning the thread upon a bobbin, re-winding with twisting upon a second bobbin having a permeable collapsible covering capable of being placed in position to protect the cake, removing the cake and covering from the bobbin, and purifying it.
- 20 3. In the manufacture of rayon, the process which comprises spinning the thread upon a bobbin, re-winding with twisting upon a second bobbin having a cloth covering, folding the cloth over the wound cake, removing the cake from the bobbin, and purifying it.
- 25 4. In the manufacture of rayon, the process which comprises spinning the thread in the gel state upon a bobbin, re-winding the gel thread with twisting upon a second bobbin having a cloth covering, folding the cloth over the wound cake, removing the cake from the bobbin, and purifying it.
- 30 5. In a method of treating spun filaments, the steps of spinning the filaments on a bobbin, rewinding and twisting the filaments onto a second supporting means, removing the filaments in the form of a cake from this second support, and wet treating the said cake.
- 35 40

6. In a method of treating spun filaments, the steps of spinning the filaments on a bobbin, rewinding and twisting the filaments onto a second supporting means, said means being covered with a covering prior to the rewinding of the filaments thereon, removing the filaments in the form of a cake from this second support, and wet treating the said cake, said covering acting to keep the filaments from tangling or knotting.

7. In a process of the class set forth, the steps of drying spool-spun filaments, rewinding and twisting them onto a second support, removing the filament body so formed, as a unit, and subjecting this body to aftertreatment and drying while in an unsupported state.

8. In a process of the class set forth, the steps of drying spool-spun filaments, rewinding them onto a second support to form a filament body comprising a tightly wound cake, removing the filament body so formed, as a unit, and subjecting this body to aftertreatment and drying while in an unsupported state.

9. In a process of the type described, the steps of spool spinning and drying filaments, rewinding the yarn into a tight cake onto second supporting means from which the cake may be removed bodily, removing the cake bodily and then wet treating and drying it while it is in an unsupported condition.

10. In the production of even shrinkage yarn, the steps of spinning filaments on a bobbin, rewinding onto secondary supports, removing the filaments bodily from said secondary supports, and wet treating and drying them unsupported.

11. In the manufacture of rayon the process which comprises spinning rayon onto a bobbin, withdrawing the rayon while rotating the bobbin, and rewinding the rayon onto a second bobbin before purifying the rayon.

CHARLES CHATIN. 49
